[57] CLAIM

The ornamental design for an automobile visor attachment, as shown.

DESCRIPTION

FIG. 1 is a top plan view of an automobile visor attachment embodying my new design.

FIG. 2 is a side elevational view thereof, the opposite side being substantially a mirror image of the side shown herein.

FIG. 3 is a bottom plan view thereof.

FIG. 4 is an end elevational view thereof taken along line 4—4 of FIG. 2.

FIG. 5 is an end elevational view of the opposite end thereof.

FIG. 1

FIG. 2

FIG. 3

FIG. 5

FIG. 4
